UNITED STATES PATENT OFFICE.

SAMUEL HENRY BYRNE, OF BRIGHOUSE, COUNTY OF YORK, ENGLAND.

PROCESS OF AND APPARATUS FOR DRAWING AND STRAIGHTENING WIRE.

SPECIFICATION forming part of Letters Patent No. 339,739, dated April 13, 1886.

Application filed March 2, 1886. Serial No. 192,758. (No model.)

To all whom it may concern:

Be it known that I, SAMUEL HENRY BYRNE, a subject of the Queen of Great Britain, residing at Brighouse, in the county of York, England, wire-manufacturer, have invented certain new and useful Improvements in Dressing and Straightening Wire and in Apparatus to be Employed Therein, of which the following is a specification.

This invention has for its object improvements in dressing and straightening wire and in apparatus to be employed therein.

At the present time wire is dressed and straightened by drawing it through dressing-plates with pins between which it is passed in a zigzag course. The wire is unwound from one drum, made to traverse the dressing-plate, and wound up again on another drum. This treatment is repeated again and again. These separate operations give rise to much loss of time and waste of material.

According to my invention, I effect several successive dressings at one operation and without winding the wire into a bundle until the end of the operation. I also combine dressing apparatus with the wire-drawing bench. After drawing the wire in succession through a number of dies at one operation, as described in the specification of a former patent granted to me, the wire, without winding it into a bundle, is caused at once to pass through the pins of the dressing-plate. One or more sets of such pins are employed, and between the dressing-plates or sets of pins (if there be more than one) the wire is passed around pulleys. These pulleys are driven at a suitable speed to bring the wire forward, and they are arranged with their axes at different angles in relation to the pins, in order that the wire may be dressed in different directions. On leaving the pins of the last dressing-plate the wire is wound upon a drum into a bundle. I also arrange dressing-machines separately from the wire-drawing bench, and in these, as above described, the wire is passed continuously through the pins of several dressing-plates. It is unwound from a bundle at the entrance end of the machine, and wound up again when the dressing operation is complete. Between each dressing-plate and the next the wire is passed around a pulley driven at a suitable

speed. The pulleys and pins are so arranged that the wire may be dressed on all sides.

In order that my said invention may be fully understood and readily carried into effect, I will proceed to describe the drawings hereunto annexed.

In the drawings, Figure 1. is a side elevation, and Fig. 2 is a plan of combined wire drawing and dressing apparatus arranged in accordance with my invention.

A A is the frame of the machine. B is a main shaft, carried in suitable bearings upon it, and driven by a belt passing around the pulleys B'.

C is the belt-fork for starting and stopping the machine.

D D are pulleys of various sizes upon the axis B. Endless cords passing around these pulleys drive intermediate shafts, E E E.

E' E' are coned pulleys upon the same shafts, and these by endless belts actuate other coned pulleys, F' F', fixed upon shafts F F at the upper part of the frame of the machine.

G G G are belt-forks, by means of which the exact position of the belts on the coned pulleys E' E' can be adjusted, so that the shafts F F F can be set to revolve precisely at the relative speeds required.

F' F' F' are drums upon the shafts F, around which the wire under process in the machine is wound. The wire is brought to the machine in a bundle, and is placed upon the drum G'. From this it passes to the first of a series of dies, H H H, each with an eye smaller than that of the die which precedes it. The dies are carried in holders, which are rotated by means of spur-teeth upon the die-holder, with which pinions I I I engage. These pinions are upon a horizontal shaft, I', on which there is a worm-wheel, I'.

K is a vertical shaft, carrying at its upper end a worm, K', engaging with a wheel, I', and so imparting rotary motion to all the dies. The shaft K is itself driven by an endless cord, 95 passing around a pulley upon it and around another pulley on a vertical shaft, L, which is driven from the main shaft B by pulleys and an endless cord, as the drawings indicate. The wire drawn from the drum G' passes 100 through the first die H of the series. Then it is lapped once or twice around the first

drum F². This drum, in rotating, draws the wire forward through the eye of the preceding die H. The wire leaving the first drum F² passes through the next die and then around 5 the next drum, and so on until it arrives at the end of the series, each die elongating the wire and reducing its sectional area. The drums, as previously stated, have their speeds accurately adjusted to the dimensions of the 10 dies. After leaving the last die of the series, the wire is lapped around the drum L' on the vertical axis L, which draws the wire through the last die and transmits it to the dressing-plate 15 M, in which dressing-pins are set in the usual manner, so that the wire laid between them is slightly deflected from a direct course.

N' is another drum on a vertical axis, N, which draws the wire forward between the dressing-pins at M and passes it forward to 20 another set of dressing-pins at O. Through these pins it is drawn by the drum P', around which the wire is lapped, and this drum is upon a horizontal axis, P, whereas the axis of the preceding drum, N', is vertical, and so, 25 also, is the axis R at the succeeding drum, R'.

Q is a dressing-plate situate between the drums P' R', and S is another dressing-plate between the drum R' and the drum T', upon which the wire is finally wound into a bundle. 30 The axis T of this drum also is horizontal or at an angle, preferably a right angle, to the axis R of the preceding drum. These various parts are driven from the main shaft B, as the drawings indicate. From a pulley, B', 35 on the shaft B, an endless band passes to a pulley, U', on the axis U. The same axis has a pulley, U², upon it, and this, by a twisted belt, drives a pulley at the lower end of the axis N. From the axis N the axis R is driven 40 by means of a pair of pulleys and a driving-belt, as shown.

U³ and U⁴ are other pulleys on the axis U, and these, by endless belts, drive the axes P and T.

45 By the compound machine shown by these drawings the wires are submitted to several drawing operations and afterward to several successive dressing operations without being wound into a bundle at any intermediate 50 stage, thereby much waste of material and also loss of time is avoided.

Although it is most convenient thus to conduct several successive drawings and several successive dressings simultaneously in one apparatus, nevertheless it is an important improvement on the present practice to combine even a single drawing operation through a single die with a single dressing operation without winding the wire into a bundle between 55 these two operations, which heretofore has been the universal practice.

Again, even when the wire is not drawn and dressed in the same machine, it is an im-

portant improvement on the present practice to pass the wire through the pins of several successive dressing-plates by the aid of winding-drums, situate between the dressing-plates, without accumulating the wire into bundles between one dressing operation and another. More especially is this improvement found 70 where the axes of the winding-rollers situate between the dressing-plates are arranged at angles the one to the other as represented by the drawings, as this insures a perfect dressing of the wire on every side.

Having now particularly described and ascertained the nature of my said invention and in what manner the same is to be performed, I declare that what I claim is—

1. The improvement in the process of dressing wire which consists in performing successive dressings at one operation by passing the wire through one set of dressing-pins, then around a drum on which it is not wound into a bundle, then through another set of pins, 80 then around another drum, and so on for as often as may be desired.

2. The improvement in the process of dressing wire which consists in passing the wire coming from a drum through a set of dressing-pins, then around a drum on an axis at an angle to that of the first drum, then through another set of pins, and so on for as often as may be desired.

3. The improvement in the process of dressing wire which consists in causing the wire to pass direct from the die to dressing-pins, through which it is dressed and straightened without winding the wire into a bundle between the die and the dressing-pins.

4. The combination, in a wire-dressing machine, of a set of dressing-pins, a drum from which the wire passes to the pins, another drum which receives the wire from these pins and which has its axis at an angle to the axis 105 of the first drum, and a second set of dressing-pins receiving the wire from the second drum, substantially as described.

5. The combination, in a wire-dressing machine, of a set of dressing-pins, a drum from 110 which the wire passes to the pins, another drum which next receives the wire, and a second set of dressing-pins receiving the wire from the second drum, substantially as described.

6. The combination, with a wire-drawing bench, of dressing-pins placed between the die or dies and the drum upon which the wire is wound into a bundle, substantially as described.

London, February 13, 1886.
